(57) **CLAIM**

The ornamental design for a fan assembly, as shown and described.

DESCRIPTION

FIG. 1 is a perspective view of a fan assembly showing our new design;

FIG. 2 is a front elevational view showing the design for the fan assembly of FIG. 1;

FIG. 3 is a rear elevational view showing the design for the fan assembly of FIG. 1;

FIG. 4 is a left side elevational view showing the design for the fan assembly of FIG. 1;

FIG. 5 is a right side elevational view showing the design for the fan assembly of FIG. 1;

FIG. 6 is a top plan view showing the design for the fan assembly of FIG. 1; and,

FIG. 7 is a bottom plan view showing the design for the fan assembly of FIG. 1.

In FIGS. 1-7, the broken line showing of portions of the fan assembly is included for illustrative purposes only and forms no part of the claimed design.
